UNITED STATES PATENT OFFICE.

JOHN H. DEENEY AND FERDINAND H. KAMPS, OF LOS ANGELES, CALIFORNIA.

COMBINED ARTIST'S CASE AND EASEL.

1,069,879.

Specification of Letters Patent. Patented Aug. 12, 1913.

Application filed October 10, 1911, Serial No. 653,818. Renewed May 24, 1913. Serial No. 769,764.

To all whom it may concern:

Be it known that we, JOHN H. DEENEY and FERDINAND H. KAMPS, both citizens of the United States, residing at Los Angeles, 5 in the county of Los Angeles and State of California, have invented new and useful Improvements in Combined Artists' Cases and Easels, of which the following is a specification.

10 This invention relates to an improvement in combined artist case and easel, and it is an object of the invention to provide a compact carrying means for conveying the materials and appliances used by an artist together with an easel for supporting the same when sketching, drawing, painting or the like.

It is also an object of the invention to provide a combined artist's carrying case and 20 a supporting easel therefor which is adapted to be folded into compact form so that the whole may be readily carried from place to place.

In the accompanying drawing forming a 25 part of this specification, Figure 1 is a perspective view of the improved carrying case and easel as set up for use. Fig. 2 is a perspective view of the front of the case when the parts have been folded in readiness 30 for portage. Fig. 3 is a rear elevation of the case showing the easel folded thereon. Fig. 4 is a detail vertical sectional view through the upper part of the easel and carrying case, showing the means whereby a 35 canvas may be adjustably held in position for work.

The details of the invention will now be more particularly described, reference being had to the said drawing in which—

40 1 indicates a case preferably of rectangular flat form, and generally approximately of the size and shape of an ordinary suit case. The casing is made open at the front and is adapted to be closed when not in use 45 as an easel, by a screen frame 2 and a palette which are adjustably secured at the opposite ends of the said case.

The casing is adapted to be set up with its longitudinal axis in an approximately 50 vertical plane and for the purpose of holding it in position for use as an easel, it is provided with adjustable easel legs and braces secured to the back of the casing as shown in Fig. 3. The legs 4 and 5 are preferably arranged at the proper angle with 55 respect to each other coming close together

at one end and spreading apart so as to pass the corners of the case at the other end. The said easel legs are adjustable, each having a fixed portion 6 fastened to the back of the case 1 and a longitudinal adjustable section 7 adapted to be drawn outwardly so as to support the whole easel structure at the proper height. The sections 7 are slotted longitudinally at 8 and 60 engage clamping pins 9 having thumb nuts 10 by which the said adjusting sections may be clamped in any adjusted position. The said leg sections 7 may thus be extended as shown in Fig. 1 to hold the case in upright 70 position to support the artist's canvas and other materials. A brace is also pivoted to the back at 12 and is provided with an extension section 13 adapted to slide upon the pivoted portion of the brace, the said extension section 13 being also provided with an elongated slot 14 which engages a clamping pin 15. A thumb nut 16 upon said pin is employed for clamping the extension section in its different adjusted positions. 75 When folded against the back of the case 1, the brace 11 preferably engages a recess formed in a projection 17 secured to the back of the casing, a turn button 18 being provided which holds the brace in its folded 80 position against the back as shown in Fig. 3. When in folded position the parts of the easel support do not project beyond the casing more than their thickness so that the 85 said parts are not in the way in carrying 90 the case. When the easel is set up, the leg sections 7 and the extension section 13 are extended as shown in Fig. 1, the case 1 being turned upon end. The front of the case is then opened by moving the screen frame 2 95 outwardly and upwardly and the palette frame 3 outwardly and downwardly. To facilitate the adjustment of the said frames 2 and 3 the frame 2 is carried by adjustable arms 19, which are pivoted to the case 1 and 100 adjustably held thereon by bolts 20 and thumb nuts 21, and pivoted to the frame 2 in like manner, and held by means of bolts having clamping thumb nuts 22 so that the angle 105 at which the said frame is placed with respect to the easel may be adjusted and controlled. The frame 2 is usually covered by a suitable artist's canvas or other material so as to properly shade the canvas upon which the artist may desire to work and which is 110 mounted in the case 1 below as indicated at 23. The frame 2 is preferably covered with

artist's canvas for the reason that it is adapted for use in producing a picture of any kind when desired. The mounting of the frame upon the arms 19 as described makes it possible to adjust the screen before the artist in an elevated position as for instance when the artist desires to stand in painting or drawing. The screen is generally turned at such a time into the position shown in dotted lines in Fig. 1 and with the frame 2 at the back of the canvas, the arms may be adjusted to higher or lower points for accommodating the screen exactly to the artist's requirements. The palette frame 3 is also mounted upon arms 24 pivoted to the case, at their inner ends and to the frame 3 at their outer ends. Clamping nuts 25 and 26 afford means for clamping the said arms 24 at different angles with respect to the case 1 and the palette frame 3 with respect to said arms and the casing 1. The palette frame 3 is provided with a recessed depression 27 forming a rabbet groove in which a palette 28 of ordinary construction may be placed. Turn buttons 29 and 30 are carried by the frame 3 for holding the palette in position in the groove 27. The palette may thus be allowed to remain in the frame 1 in use by the artist or it may be taken therefrom and held in the hand in the usual way.

The case 1 is provided with a partition 31 which divides the space closed by the frame 2 from that closed by the frame 3, the said frames just fitting over said spaces as shown in Fig. 2. Below the partition 31 considering the same when the easel is set up, one or more partitions 32 and 33 are employed for forming compartments in the casing for receiving the artist's materials; thus an elongated compartment 34 may be provided for the artist's brushes and a large rectangular compartment 35 may be provided for paints and other materials while a larger compartment 36 may be also formed for carrying other articles, as for instance a folding camp stool or other rest for the artist. The space in the case 1 upon the other side of the partition 31 is preferably arranged to receive one or more canvases usually stretched upon frames for artist's work. The said canvases may be properly held in place and spaced from each other by means of cleats 37 and 38 which extend along the inner surface of the walls of the case 1. A hinge cover 39 is secured to the upper end of the box and is adapted to be folded down over the edges of the canvases when they are packed within the case.

In using the easel a canvas as 23 may be left in position between the cleats in the case or may be set forward upon the partition 31 and tipped outwardly to any desired degree as shown in Fig. 4. In this instance an adjustable bar 40 is provided upon

the cover 39, its outer end being formed with canvas engaging projections 41, while its inner end is adapted to be slipped into a clamp 42 carried upon the cover 39, the said clamp having a thumb screw 43 for impinging upon the bar 40 and holding it in adjusted positions. The use of such a bar is advantageous since it permits of the tipping of the easel backwardly from the artist and yet permits of his arranging the canvas upon which he is working at any desired angle.

The casing 1 is provided with any suitable handle 44 by which it may be carried when in folded shape. The cover 39 is usually provided with a hook 45 or other suitable latch which is arranged to engage an eye 46 upon the frame 2 when the case is closed.

It will be observed that the easel is not only well adapted for use in supplying all the needs of an artist in the field or elsewhere, but when folded is adapted to receive and carry all of the appliances and materials which the artist may desire to carry with him. Such materials and appliances usually make a very heavy package or bundle to be carried from place to place but by the use of the easel described the weight which must be carried is greatly reduced and the device may be carried in compact form.

What we claim is:

1. An easel comprising a carrying case having adjustable supporting leg portions secured thereto, an adjustable palette, and an adjustable screen adapted to form the front of said casing when it is carried from place to place, and means for holding said palette and screen in their different adjusted positions.

2. An easel comprising a carrying case adapted to be set upon end when used as an easel, a supporting tripod connected with said case for holding it in easel position, a palette adapted to form part of the front wall of the casing, adjustable arms carrying the same, a screen also adapted to form a portion of the front of the casing, adjustable arms carrying the said screen, and a hinged end portion for completely closing the casing when it is carried from place to place and yet permitting of the arrangement and withdrawal of a canvas to be painted.

3. A combined artist's case and easel comprising an elongated receptacle, a tripod arranged longitudinally of the back thereof for supporting it in easel position, one wall of said receptacle when in closed position being made up of a palette carrying frame and a screen carrying frame, arms adjustably secured to the palette frame and adjustably connected with the receptacle for holding the palette in operable position and acting as hinges for the closing of the said receptacle by the palette frame, and arms adjustably connected with the screen frame

and also having adjustable connection with the receptacle for holding the screen in different positions and acting as hinges for the folding of the frame in the closing of 5 the receptacle.

4. An easel structure comprising a casing, an adjustable easel support therefor, the said casing having compartments formed therein, means for holding a canvas or other work- 10 ing surface in position in one of said compartments, a screen frame adjustably carried by the casing, a palette frame adjustably mounted on the casing, the said screen

frame and palette frame being adapted to close the front of the casing and an edge 15 cover adapted to fold over the end of the case for entirely closing the same.

In witness that we claim the foregoing we have hereunto subscribed our names this 11th day of July, 1911.

JOHN H. DEENEY.
F. H. KAMPS.
